EAVES TROUGH BRACKET

Louis L. Ramser, Jr., Louisville, Ky.

Application May 26, 1950, Serial No. 164,311

11 Claims. (Cl. 248—48.1)

1

This invention relates to an improved hanger or bracket for eaves troughs or gutters.

It is an object of my invention to provide a rigid support for eaves trough which is strong enough to prevent the trough being pulled down by accumulations of ice or snow liable to be encountered during the winter season.

A further object is the provision of a gutter bracket which does not require to be attached to the roof surface, and thus can be used for repair work on slate or tile covered roofs without the need for removing part of the roof covering.

Still another object is the provision of a relatively inexpensive gutter bracket made from sheet stock, which can be secured easily to the facia board, and in which the tensile strength of the sheet is utilized to support the gutter.

Another object is the provision of a gutter bracket which supports the gutter in a manner to resist deformation of the gutter under loads.

In accordance with the present invention, a gutter bracket is constructed having a tubular portion to receive a spike by which it is secured to the facia board of the eaves, and a flange or web portion extending from said tubular portion and terminating in an edge adapted to abut the facia board. The web may be reinforced by flanges at its edges to increase the resistance of the web to lateral bending or buckling. In such brackets for use with semi-circular gutters, said web may be interrupted, one part extending from the facia board to the outside wall of the gutter, and the other part extending from the inside wall of the gutter from a point directly opposite to the tubular section. As the two sections of the web engage the gutter wall in registering relation on opposite sides of the gutter wall, in effect they form a continuous reinforcing web. The improved gutter bracket is fastened to the facia board by a spike passing through the tubular section and through the outer edge of the gutter, and is sufficiently strong that any normal failure of the bracket will come from the spike pulling out of the facia board rather than by bending of the gutter bracket.

The invention will be described in greater detail in connection with the accompanying drawings illustrating embodiments of the invention by way of example, and wherein:

Figure 1 is a side elevation of an embodiment of the invention applied to a colonial type gutter shown in section,

Figure 2 is a section of the bracket taken on line 2—2 of Figure 1,

2

Figure 3 is an enlarged sectional view of a detail,

Figure 4 represents a schematic layout of the bracket on a sheet,

5 Figure 5 is a side elevation of a modification applied to a half round gutter, and

Figure 6 represents a schematic layout of the modification shown in Figure 5.

10 Figure 7 is a side elevation of a modification ogee type gutter.

Figure 8 represents a schematic layout of bracket modification shown in Figure 7.

15 Referring to the drawing, Figures 1 to 4, the bracket may be constructed of sheet metal bent

20 to shape, and comprises a sleeve 1 which has depending ribs or webs 2, 3 tapering generally in width toward the facia board end, and terminating in flanges 4, 5 at the facia board end. The webs 2 and 3 may be secured together, if desired, by spot welding or in any other suitable

25 manner to provide in effect a web of double thickness, and the exterior or sloping edges of the web may be flanged at 7 and 8 to provide additional resistance to lateral buckling. Additional

30 strength in the web may be secured by punching out a hole 9 in each web and striking up the metal at the hole, as indicated at 10, and flanges may be provided at the front and bottom edges 11 and 12 respectively. The bracket may be constructed from a generally T shaped sheet

35 metal blank as shown in Figure 4 by punching out the holes 9, 9' and striking up the metal around the holes and bending over the flanges on the dot and dash lines, then bending the blank at the middle to form the sleeve 1.

A gutter or trough of the colonial type is shown in Figure 1, and has a back wall 14, and a generally ogee front wall 15 terminating in a bead or flange 16. In attaching the gutter to

40 a roof, a hole is punched in the front wall at 17, a spike 18 is passed through the hole into sleeve 1, and the spike is driven through the back wall 14 into the facia board 19 of the eave and into the end of a joist 20 abutting the facia board. This brings the flanges 4 and 5 against the back wall 14 of the gutter and, if desired,

45 nails 21 may be driven through holes 22 formed therein and through the back wall into the facia board to further insure the bracket from turning about the spike as a pivot. The lower edge 7, 8 and flanges 12 of the web are sufficiently above the bottom of the gutter so as not to obstruct the flow of water or leaves from trees, etc. therethrough.

50 55 There is thus provided a strong rigid bracket

for supporting the gutter. The tubular part 1 cannot bend because it contains the spike which prevents collapse of its walls, and bending is further resisted by the median webs 2, 3. Buckling of these webs is resisted by the struck up portions 10, the flanges 7, 8 and the welding together of the two webs. The bracket is made of relatively thin gauge sheet metal, yet is so strong that the only way the gutter can be pulled down or caused to sag is by the spike pulling out of the facia board and joist. However, the spike is of such length that it penetrates the facia board for about two inches. This offers sufficient resistance to withdrawal of the spike so that the gutter will not pull down or sag under the most severe conditions encountered in practice. The brackets may be located at any suitable distance apart along the gutter, as their construction does not limit their application to any particular part of the facia board. The bracket requires relatively little metal, and can be constructed cheaply of scrap material found in tin and roofing shops, by stamping and bending operations. However, if desired, the bracket may be constructed as a casting or forging, or in any other manner desired.

In the modification shown in Figures 5 and 6, the details of construction are modified for supporting half round gutters. The bracket comprises a strip of sheet metal 25 bent double to provide a tubular part 1, and middle webs 26, 27 which are flanged at the edges at 7 and 8. The rear edges 28 and 29 are formed on an arc and are flanged, so that the edges correspond to the curvature of the inside of the half round gutter 30. The piece 25 connects to an enlarged portion 31 which is bent back upon itself at the edges to provide flanges 32 and web portions 33, 34, the latter being curved at the edges 36, 37 to correspond to the outside of the gutter and are flanged. The two webs may be fastened together by spot welding, if desired.

In this modification the flanges 32 abut the facia board on the outside of the gutter, and the webs 33, 34 span that part of the distance between the flanges and tube 1 which lies between the flanges and the outside wall of the gutter, while the webs 26, 27 span the remaining distance between the tube 1 and the inside of the gutter. As the two parts of the web inside and outside the gutter are directly opposite, they form in effect a continuous web between the tube 1 and flanges 32 which supports and reinforces the tube 1 in the same way as in the modification described in connection with Figures 1 to 4. In this embodiment the spike holds firmer because the pivot or fulcrum for pulling out the spike lies at 39 so that in order for the spike to pull out it must bend upward where it enters the facia board.

The curved flanges and the webs 33, 34 may extend outwardly as far as desired, but preferably do not extend beyond the center of the trough, so that water flowing down the outside face of the trough will not be trapped between the trough wall and bracket where it would lie and cause rusting. Also, if desired, the flanges 26, 27 may be omitted from the sleeve 1, in which case the trough would be supported at the bottom exteriorly, and would be held against collapse by the spike 18 and sleeve 1. In this case, web 25 also could be omitted.

In the modification shown in Figures 7 and 8, the flanges 2, 3 are tapered and are of reduced

height so as to provide more space beneath for passage of leaves and other debris. Flanges 7 and 8 may be provided to increase resistance to bending. The front and rear edges of the tubular portion 1 are flanged as indicated at 41 and 42. These flanges engage the interior face of the gutter and prevent entrance of moisture to the spike. The layout for this modification is shown in Figure 8 wherein the dot-and-dash lines show the lines of fold in the blank.

The invention may be embodied in various other forms without departing from the spirit or scope thereof.

I claim as my invention:

1. A gutter bracket comprising a tubular member adapted to be received in a horizontal position in a gutter between the front wall and the back wall thereof; and a web extending substantially vertically from said tubular member and terminating at a substantially vertical base line adapted to abut the facia board of an eave, said web being flanged at the edge abutting the eave.

2. A gutter bracket as specified in claim 1 wherein flanges extend laterally from said web at said base.

3. A gutter bracket as specified in claim 1 wherein said web is of generally triangular form with its apex at the front end of said tubular member.

4. A roof gutter bracket comprising a tubular member; a substantially vertical flange extending at right angles to the axis of said tubular member and adapted to abut a facia board; and web means extending substantially in the plane of said axis between said tubular member and flange.

5. A gutter bracket as specified in claim 4 wherein said web is divided on an arcuate edge for reception of a gutter wall.

6. A gutter bracket comprising a sheet metal piece curled to provide a tubular portion with a web portion extending from said tubular portion and terminating at a base substantially in line with one end of the tubular portion, said base being bent to provide at least one flange adapted to engage a facia board.

7. A gutter bracket comprising a sheet metal piece curled medially to provide a tubular portion with webs extending from said tubular portion and terminating at a base substantially in line with one end of said tubular portion; said base being bent to provide flange extending transverse to said web.

8. A gutter bracket as specified in claim 7 having means to secure said flanges together.

9. A gutter bracket comprising a sheet metal piece curled medially to provide a tubular portion for receiving a spike; flanges connected to said tubular portion and extending transversely at right angles to said tubular portion for engaging a facia board; and webs extending between said tubular portion and flange for supporting said tubular portion.

10. A gutter bracket as specified in claim 9 wherein said webs are secured together, and are each divided arcuately to receive a gutter wall.

11. A gutter bracket comprising a web portion terminating at one edge in flanges adapted to be attached to a facia board, the other edge being curved to engage the outside of a gutter.
